UNITED STATES PATENT OFFICE.

ALBERT BEE CARSON, OF PAPINSVILLE, MISSOURI.

SAFETY-POCKET.

SPECIFICATION forming part of Letters Patent No. 243,506, dated June 28, 1881.

Application filed March 23, 1881. (No model.)

To all whom it may concern:

Be it known that I, ALBERT B. CARSON, a citizen of the United States, and residing in Papinsville, in the county of Bates and State 5 of Missouri, have invented a new and useful Improvement in Safety-Pockets, of which the following is a specification.

The object of my invention is to furnish a pocket which can neither be picked nor cut 10 open without the knowledge of the wearer, and which may be put in the place of the ordinary pockets in coats, vests, pantaloons, or other articles of wearing-apparel.

My invention consists in providing a pocket 15 with a mouth-piece consisting of two plates of steel or other suitable material, the main or back plate having its extremities slotted and bent upon itself, and the front plate having its extremities fitted to slide in the slots of 20 said back plate, and provided with T-shaped ends to prevent it slipping from place.

It further consists in quilting rubber strips lengthwise and crosswise of the front of the pocket.

25 In the drawings, Figure 1 is a front elevation of my invention. Fig. 2 is a vertical section of the same. Fig. 3 is a horizontal section.

The front of the pocket A is composed of two pieces of cloth or other suitable material, 30 between which strips of rubber a are quilted lengthwise and crosswise, and is sewed to the leather covering of the front plate, B. The extremities of the front plate, extending beyond the leather covering, work in slots C in the 35 bent ends of the back plate, D, and are held in place by the T ends E. The ends of the back plate, D, are bent upon the latter and tempered, if of steel, in that position, so as to form springs to keep the pocket closed, which 40 is its normal condition, while the slots in the springs, in conjunction with the T-shaped ends of the front plate, allow the spreading apart of the plates to give access to the pocket.

The operation of the invention is as follows: When the mouth of the pocket is forced open 45 the front plate draws forward the extremities of the back plate, while the extremities of the front plate slide through the slots in said back plate until stopped by the T-shaped ends coming in contact with the sides of said slots. 50 When released, the spring action of the back plate causes the front plate to instantly resume its first position and shut closely the pocket. The rubber bands a are used to prevent the pocket from being cut without the knowledge 55 of the wearer, such bands being practically so difficult and requiring such force to sever that it is impossible to cut them without giving warning to the wearer.

I am aware that safety-pockets are not 60 broadly new; but heretofore the bodies of the pockets have been protected by metal chains, which are undesirable, not only because of their weight, but also because of their liability to rust and stain the clothes. I do not therefore 65 claim, broadly, a safety-pocket; but

What I do claim is—

1. A safety-pocket constructed, substantially as described, of the front, A, having rubber strips a quilted lengthwise and crosswise therein, the plate D, provided with bent springing ends, in which are formed slots C, and plate B, having T-shaped ends E, as and for the purposes set forth. 70

2. In a safety-pocket, the combination, with 75 the body of the pocket A, of the closing device, substantially as described, consisting of the plate D, provided with bent slotted ends, and the plate B, with T-shaped extremities to engage therewith, whereby the pocket is automatically closed, as and for the purposes set forth. 80

ALBERT BEE CARSON.
